US00D835459S

(12) **United States Design Patent** (10) Patent No.: **US D835,459 S**
 Sedgwick (45) Date of Patent: **** Dec. 11, 2018**

- (54) **STACKABLE FOOD CONTAINER LID HAVING A CONDIMENT CONTAINER RECESS**
- (71) Applicant: **Inno-Pak, LLC**, Delaware, OH (US)
- (72) Inventor: **Nathan Sedgwick**, Aliso Viejo, CA (US)
- (73) Assignee: **Inno-Pak LLC**, Delaware, OH (US)
- (**) Term: **15 Years**
- (21) Appl. No.: **29/624,536**
- (22) Filed: **Nov. 1, 2017**
- (51) LOC (11) Cl. **07-99**
- (52) U.S. Cl. **D7/392.1; D7/392**
- (58) **Field of Classification Search**

Primary Examiner — Karen S Acker*Assistant Examiner* — Steven B Reinholdt, Jr.*(74) Attorney, Agent, or Firm* — Ward and Smith, P.A.;
Ryan K. Simmons(57) **CLAIM**

The ornamental design for a stackable food container lid having a condiment container recess, as shown and described.

DESCRIPTION

FIG. 1 is a front perspective view showing my new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.
 In the drawings, the broken lines and the areas within them illustrating a food container bottom depict environmental subject matter that forms no part of the claimed design.

1 Claim, 7 Drawing Sheets---
